DISPENSING APPARATUS

Le Roy C. Van Brunt, Palmer, Mass., assignor to Westinghouse Electric Corporation, East Pittsburgh, Pa., a corporation of Pennsylvania

Filed May 23, 1958, Ser. No. 737,265

5 Claims. (Cl. 312—45)

This invention relates to dispensing apparatus, and more particularly to an improved dispensing machine in which bottles of one or more sizes can be stored and dispensed.

This invention is particularly applicable to that type of dispensing machine having a storage magazine including a plurality of side-by-side compartments for storing bottles in vertical stacks or rows. To be easily serviced, magazines for bottle dispensing machines must be so constructed as to permit the supply of bottles to be replenished quickly and conveniently. The peculiar configuration of soft drink bottles generally does not permit them to be stacked in a stable manner and there is generally a tendency for the bottles to slide on one another and fall out of the magazine if they are not retained therein by some dependable means.

The invention is also applicable to a versatile dispensing machine of the type having a storage magazine which is capable of storing and dispensing any one of several sizes of bottles or a load of bottles including more than one bottle size.

In accordance with the present invention, there is provided, in a bottle dispensing machine, an open front storage magazine having a plurality of side-by-side compartments for storing bottles in vertical stacks or rows, and a pair of upright, elongated members. The members are arranged in rearwardly converging relationship and spaced apart to define a vertically elongated slot within each compartment for dependably holding the bottles at the neck. One of the upright members serves to retain the bottles by engagement of its edge with the enlarged or shoulder portions of the bottles, and, in order to take the stress of the bottles without damage to itself this upright member is made of rigid construction. The other upright member is made either partly or wholly of flexible material and it serves principally to retain the neck of the bottle in engagement with the rigid strip. The flexible strip, however, permits the bottle to widen the slot when it is forced thereagainst during loading of the magazine, so that the enlarged crown end above the neck of the bottle can pass through. In addition the edge of the rigid member is positioned rearwardly of the edge of the thin flexible strip to insure that the rigid strip takes the stress of retaining the bottles, thereby minimizing wear and damage to the flexible strip. It is a feature of this invention that the bottle holding means does not obstruct the open front portion of the magazine, thus conserving space and facilitating the loading of bottles.

The various objects, features and advantages of this invention will appear more fully from the detailed description which follows, taken in connection with the accompanying drawings, forming a part of this application, in which:

Fig. 1 is a horizontal sectional view of a dispensing machine magazine embodying the invention;

Fig. 2 is a front elevational view of the dispensing machine magazine of Fig. 1 and from which details of

2

the releasing mechanism have been omitted for the sake of brevity;

Fig. 3 is an enlarged horizontal sectional view of the article retaining means of the dispensing machine magazine of Fig. 1; and

Fig. 4 is an enlarged horizontal sectional view, similar to Fig. 3, but showing the article retaining means in modified form.

The invention is applied to a magazine suitable for use in a dispensing machine. Included in the magazine are a plurality of vertical partitions or walls 10 which divide the magazine into a plurality of side-by-side storage compartments 11 for storing capped bottles 12 one upon the other in vertical stacks or rows. The walls 10 are braced in position by angle braces 13 and 14, which also serve to connect the walls 10 to top and rear panels 15 and 16, respectively, of the magazine. The compartments 11 are open at the front side to permit the bottles 12 to be inserted therein, capped end first, for retention by the bottle retaining means of this invention.

The bottles 12 shown in the drawings are of large (12 oz.) and small (6 oz.) size, the largest and smallest sizes currently dispensed by machine. These bottles 12, as well as bottles of similar and intermediate sizes, have a common cap end configuration; that is, each bottle 12 has a reduced, neck portion 18 and an enlarged, shoulder portion 19 similar to corresponding portions of other bottles, so far as their respective external dimensions are concerned. The bottle retainers hold bottles by the neck and, even though these retainers are uniformly constructed, they are capable of holding many sizes of bottles.

The bottle retainer illustrated in Figs. 1, 2 and 3 includes a rigid member 20 and a partly flexible member 21, which members are elongated, upright, and arranged to extend, respectively, from opposite walls 10 rearwardly and toward each other, in rearwardly converging relationship. The members 20 and 21 terminate in vertical edge portions spaced from, but near, the rear panel 16, in spaced relation to each other, thereby defining a vertically elongated slot 24 between them. Each slot 24 is of a uniform size that is slightly larger than the neck 18 of a bottle 12 so that the bottles are capable of unrestricted downward movement. However, the slot is narrower than the shoulder portion 19 of the bottles 12, so that the upright member 20 engages the shoulder portion 19 and holds the stack in proper front-to-rear position when the stack of bottles is either stationary or moving downwardly toward the releasing mechanism.

Construction of the upright members 20 and 21 is facilitated by forming them as bifurcations of the walls 10. Each wall 10 and its members 20 and 21 appear generally Y-shaped when viewed edgewise, as in Figs. 1 and 3. The member 20 extends into a compartment 11 abutting one side of the wall 10 and consists of the free end of the sheet metal material from which the wall 10 is constructed. The other member 21, however, extends into the compartment 11 abutting the other side of the wall 10 and includes a portion thereof which is of double thickness, since it is formed as a flat rolled pleat integrally connecting the wall 10 and the member 20. By forming the wall 10, the member 20, and a section of the other member 21 from a unitary metal sheet of suitable thickness, these parts are given sufficient structural rigidity to resist the deforming forces of the stacked bottles.

It is a principal feature of the present invention that the member 20 is of rigid construction, so that this member resists deformation and damage to itself while preventing the stored bottles 12 from moving forwardly out of the magazine.

In order to provide means for admitting the capped ends of the bottles 12 to the rear of the slot 24, a separate edge

section or strip 23 for the member 21 is formed of stainless spring steel or other corrosion resistant resilient material and is fastened by suitable means between the pleated rigid section of the member 21 and a rigid, vertically extending clamping strip 25. The fastening means for the member 21 prevents the pleat from unfolding. In addition, the strip 23, being resilient, is capable of flexing rearwardly when the capped end of a bottle 12 is forced thereagainst during loading, thereby widening the slot 24 and allowing the capped end of the bottle to pass therethrough. Once the bottle 12 is in position, the edge strip 23 returns to unflexed position, where it is in position to exert a lateral bias on the neck of any bottle which attempts to move out of engagement with the rigid member 20. By this arrangement, the edge strip 23 insures that the rigid member 20 will engage the bottles 12 at their shoulder portion 19 and prevent their longitudinal movement toward the front of the magazine.

Preferably, the resilient strip 23 should flex with less resistance during rearward movement, when admitting the capped end of a bottle through the slot 24 to stored position, than during attempted forward movement, when it prevents bottles from moving forwardly from stored position. In order to accomplish this difference in resistance for respective movements in opposite directions, the rigid clamping strip or member 25 is disposed on the front side of the resilient strip 23. The clamping strip 25 extends with the resilient strip 23 and the pleated section away from the fastening means, toward the slot 24. The clamping strip 25 terminates short of the article-engaging edge of the clamping strip 25 but closer to the slot 24 than the pleated section of the member 21, thus exposing a substantial extent of the resilient strip 23 for engagement by the bottles 12 (see Fig. 3). Since a cantilever's resistance to bending depends not only on its cross-sectional properties, but also its unsupported or free length in bending, it follows that when the resilient strip 23 is flexed for rearward movement it bends with less resistance about the pleated section of the member 21 than when a smaller portion thereof is flexed for forward movement about the clamping strip 25.

The vertical edge portion of the member 20 is positioned rearwardly of the vertical edge portion of the flexible edge strip 23 by a small distance, such as one-eighth of an inch, so that the rigid member 20 would first contact the shoulder 19 of the bottle if it were to move forwardly, the purpose of this arrangement being to minimize the amount of rubbing contact and consequent wear on the relatively thin edge of the strip 23. Preferably, the member 20 and the member 21 including its edge strip 23 extend into the compartment 11 at an angle of no less than 45° with their respective walls 10 so that they hold the bottle 12 in a more positive manner. An included angle of less than 45° increases the chances of a bottle working its shoulder portion 19 outwardly past the edge of the members 20 and 21, thereby causing the crown or cap to catch in the slot 24 and restraining the bottle from downward movement. On the one hand a small included angle makes it easier to push the crown of a bottle through the slot, while on the other hand a large included angle holds the bottles more positively, and for this reason an angle of from 45° to 60° is thought to be a desirable range.

Fig. 4 illustrates modified bottle retaining means embodying the invention which are formed separately of the wall 10 and suitably secured to the rear panel 16 of the magazine. The modified bottle retainer includes an upright, U-shaped channel 31 and a pair of upright members 32 and 33, each of which is integrally and rigidly connected to the channel along the longitudinal edge thereof, with an included angle of approximately 45° between each member and the plane of the wall 10 adjacent thereto. By this arrangement, the members 32 and 33 occupy positions in their associated compartment 11 of the assembled magazine that are similar to their counterparts, members 20 and 21, of the previously

described embodiment. In other words, the members 32 and 33 extend from the channel 31 inwardly and toward the rear of the compartment 11 and terminate in vertical edge portions that are spaced apart to define a vertically elongated slot adjacent the rear panel 16 of the compartment. So that the members 32 and 33 will function in a manner similar to the members 20 and 21 of the previously described embodiment, the member 33 includes a flexible strip 36 of resilient material which is suitably secured to a rigid portion of the member 33, as by screws and a clamping strip 37, along the length of one longitudinal edge thereof. A structural feature of the flexible strip 36 that distinguishes it from the flexible strip 23 of the other embodiment is a longitudinal strip 38 of hard, wear-resistant material which is secured, as by welding, to the other longitudinal edge of the strip 36 in order to provide a durable contact edge for the thin, flexible strip 36 of the member 33. The wear-resistant strip 38 and the flexible strip 36 of the member 33 cooperate to provide the modified bottle retainer with a portion thereof that is capable of flexing rearwardly to admit the capped ends of bottles 12 through the slot 34, and which returns to unflexed position to retain the bottles at the neck from movement toward the front opening.

From the foregoing it will be apparent that an improved bottle retainer has been provided which is simply and inexpensively constructed, but at the same time is rugged and dependable in service, all of which is attributable to the unique use and positioning of one rigid member and one flexible or partly flexible member in making this bottle retainer.

While the invention has been shown in several forms, it will be obvious to those skilled in the art that it is not so limited, but is susceptible of various other changes and modifications without departing from the spirit thereof.

What is claimed is:

1. In apparatus for dispensing articles having neck and shoulder portions near one end thereof, a magazine adapted to store a row of said articles and having a front opening for admitting articles thereto, and article retaining means for each row of articles comprising a pair of elongated members for retaining said articles at their neck and shoulder portions, said members being arranged on opposite sides of said row, each of said members having an edge portion, said edge portions being disposed rearwardly of said front opening and spaced apart to define an elongated slot therebetween, said slot being wider than said neck portion of said article and narrower than said one end of said article, one of said members being rigidly constructed, the other of said members comprising an elongated flexible strip of resilient material, said edge portion of said one member being positioned rearwardly of said edge portion of said other member, whereby said edge portion of said one member takes the stress of retaining said articles and minimizes wear to the edge portion of said other member.

2. In apparatus for dispensing articles having neck and shoulder portions near one end thereof, a magazine adapted to store a row of said articles therein and having a front opening for admitting articles thereto, and article retaining means for each row of articles comprising a pair of elongated members for retaining said articles at their neck and shoulder portions, said members being arranged on opposite sides of said row in rearwardly converging relationship, each of said members having a longitudinal body portion and an edge portion, said edge portions being spaced apart to define an elongated slot therebetween, said slot being wider than said neck portion of said article and narrower than said one end of said article, one of said members being rigidly constructed, the other of said members comprising an elongated, flexible strip of resilient material, said edge portion of said one member being positioned rearwardly of said edge portion of said other member.

3. In apparatus for dispensing articles of the type hav-

ing neck and shoulder portions near one end thereof, a magazine adapted to store said articles one upon the other in stacked relationship and having a front opening for admitting articles thereto, and improved article retaining means comprising a pair of spaced, upright, article retaining members defining a vertically elongated slot therebetween, the first of said members including a vertical portion of rigid material and a vertical strip of resilient material connected to said vertical portion along the length thereof, said resilient strip extending rearwardly in said magazine and toward said other member and terminating in a longitudinal edge portion, the other upright member being rigidly constructed and extending rearwardly in said magazine and toward said first member, and terminating in a longitudinal edge portion which is positioned rearwardly of the edge portion of said first member, said first member being arranged so that at least a portion of said resilient strip is flexed when said one end of an article is forced thereagainst to enlarge at least a portion of said slot and admit said one end of the article, the construction and arrangement being such that said resilient strip returns to unflexed position and assists said other upright member in retaining the neck portion of said article in said slot.

4. In apparatus for dispensing capped articles having neck and shoulder portions near the capped end of the article, a magazine having a plurality of walls forming at least one vertically elongated compartment adapted to store said articles one upon the other in stacked relationship and a front opening for admitting articles to said compartment, and improved article retaining means comprising a pair of upright members, said members being arranged on opposite sides of said compartment in rearwardly converging relationship, said members having vertical edge portions spaced from each other to define a vertically elongated slot therebetween, one of said members being rigidly constructed, and the other of said members having a vertical strip of resilient material along the said edge portion thereof, said other member being arranged so that the vertical strip is flexed when the capped end of said article is forced thereagainst to widen

5 said slot and admit the capped end of the article therethrough, said edge portion of said rigidly constructed member being positioned rearwardly of the edge portion of said other member to engage the capped end of said articles and prevent movement thereof through said slot toward said front opening.

10 5. In apparatus for dispensing capped articles having neck and shoulder portions adjacent the capped end of the article, a magazine having a rear wall and a pair of side walls forming at least one vertically elongated compartment adapted to store said articles therein in stacked relationship and a front opening for admitting articles to said compartment, and improved article retaining means including a pair of upright members, said members being arranged in rearwardly converging relationship, each of said members having a vertical edge portion near the rear wall of the compartment, said edge portions being spaced from each other to define a vertically elongated slot therebetween, one of said members 15 being rigidly constructed and having its edge portion positioned rearwardly of the edge portion of the other member, said other member comprising a vertically elongated strip of wear-resistant material disposed along said edge portion thereof and a vertically elongated strip of resiliently flexible material connected between said wear-resistant strip and said rigid portion, the construction and arrangement being such that said resilient strip is flexed and said wear-resistant strip is movable rearwardly when the capped end of said article is forced against 20 30 said other member to widen said slot and pass the capped end of the article therethrough, after which said resilient strip unflexes and said capped end of said article is engaged by said rigid member to prevent movement of said 35 capped end through said slot toward said opening.
